United States Patent Office

Des. 183,033
Patented June 10, 1958

183,033

STOVE MAT OR THE LIKE

Earl S. Tupper, Smithfield, R. I., assignor to Tupper Corporation, North Smithfield, R. I., a corporation of Delaware

Application July 15, 1957, Serial No. 46,940

Term of patent 14 years

(Cl. D9—6)

Figure 1 is a top plan view of a stove mat or the like embodying my new design, it being understood that the full representation is repeated in the broken line portion;

I claim:

The ornamental design for a stove mat or the like, substantially as shown and described.
